APPARATUS FOR MOUNTING SAMPLES ON CARDS AND THE LIKE

Alfred Oser, Vienna, Austria

Application October 26, 1937, Serial No. 171,071
In Germany November 9, 1936

24 Claims. (Cl. 216—2)

The invention relates to apparatus for mounting samples, especially textile samples, on cards or other kinds of backing. In particular, it relates to such an apparatus in which beneath a vertically movable card carrier there is provided a slide upon which an adhesive-container and a sample-container are so mounted that in the one end position of the slide the adhesive-container, and in the other the sample-container faces the card, so that in one working operation the application of the adhesive to the cards and in a second working operation the pressing of the areas thus coated with adhesive against stacks of samples provided in the sample-container takes place. An apparatus of this type is described in my U. S. Patent No. 1,943,390, filed September 26, 1931, patented Jan. 16, 1934.

Sample cards produced with the aid of the known apparatus look much better than hand stuck cards; but large scale production does not proceed as fast as is desirable, because the operation of the apparatus necessitates a large number of individual manipulations. The attendant has to insert into the card carrier the card to which adhesive is to be applied, and to remove the card from the sample-container after the samples have been mounted thereon, and also to apply adhesive to the adhesive applying pads provided in the adhesive-container, if their sucking action has become too small, and in fact he has to perform at each working cycle a number of manipulations which are too varied to admit of their being carried out in a uniformly recurrent manner to a set beat.

The principal object of the invention is to produce an apparatus for mounting samples on cards or the like which is fit for a large scale production, limiting the working of the attendant to removing the card from the sample-container after the samples have been mounted thereon by the apparatus.

A further object is to provide an apparatus in which simultaneously with the mounting of the samples the cards are printed with the aid of printing blocks or forms in a simple and efficient manner. It is already known to number sample cards by means of negative matrices associated with the sample-containers, but the results obtained have generally not been satisfactory, since the individual matrices used for any one card are apt to be worn to different extents.

In accordance with the invention the problem taken is solved in such a manner that a device for inserting a card in the card carrying head of the apparatus and an inking mechanism for ink-

ing printing forms associated with the sample-container are controlled by the slide carrying the adhesive and sample-containers.

The device for inserting the cards in the head preferably consists of gripping elements which withdraw the uppermost card from a stack of cards, and which are controlled by the slide when the latter is moved in the direction towards the gripping elements, and present the card to clamping means associated with the slide and adapted, on the movement of the slide in the other direction, to draw the card into guides provided on the carrier. As gripping elements there may with advantage be used rolls or the like the periphery of which is preferably provided with a rubber covering.

Another object is to provide means, in such an apparatus for automatically wetting the adhesive applying members, preferably in the form of pads of absorbent material, with adhesive so as to ensure uniform application of adhesive to the cards. Suitably, this wetting device is controlled by the card carrying head of the apparatus.

A still further object of the invention is to provide means, such an apparatus, for automatically inking the forms or printing blocks, in a uniform and thorough manner. To this end the inking mechanism for the inking of the printing forms associated with the sample-container is equipped, in accordance with the invention, with an inking roll mounted on a pivoted lever which is so controlled by the slide of the apparatus that in one end position of the lever the inking roll engages the distributing roll of the inking mechanism and in the other end position of the lever the inking roll travels over the face of the printing forms.

Another object is to provide means, in such an apparatus, for ensuring that the forms are all evenly pressed against the cards. This is achieved, according to the invention, by supporting the forms on resilient pins.

Still another object of this invention is to provide means, in such a device, for avoiding smudging of the wet print on the cards. It might happen that after the printing of the card, and during the movement of the sample-container to the end position that the card becomes unintentionally shifted and thus the print thereon smudged. To obviate this danger, it is advisable to bring the cards out of contact with the types so that the printed impression of the card shall be cleared. To this effect the sample-container, according to the invention, is adapted to be raised and lowered independently of the printing forms, so as to en-

able the types of the forms to be submerged beneath or protruded above the surface of the sample-container. The sample-container is preferably supported upon axially slideable resilient pins 5 to which, on the movement of the sample-container, there is imparted an up and down movement, i. e., by levers controlled by stationary guides and by a helical cam groove. The guides are secured to the bed of the apparatus at such 10 points that the sample-container on its movement along the bed is lowered before the inking of the types and raised before the printing of the cards takes place.

A further object of the invention is to provide 15 an apparatus of the type described which enables the preparatory work required for inserting fresh samples and forms in the container to be done independently of the apparatus so that time is gained in going over to the production 20 of a fresh set of sample cards. For this purpose the boxes for the stacks of samples and the forms are placed in an intermediate container adapted to be inserted in the sample-container of the apparatus. When the stacks of 25 samples in the intermediate container have all been gummed on the cards or a set of cards with different samples is to be made, the intermediate container is removed from the apparatus and replaced by another intermediate container 30 freshly filled with samples and forms.

A still further object of the invention is to provide an apparatus of this type which enables the subsequent pressing of the sample cards necessary to ensure that the samples firmly adhere 35 to the cards, to be carried out in a shorter time than was required hitherto. To this end, the cards are passed through a pair of rollers after the samples have been mounted thereon.

Other objects and features of novelty will 40 become apparent as this specification proceeds, in connection with the accompanying drawings showing a form of construction of the apparatus according to the invention, by way of example, in which:-

45 Fig. 1 is a front elevation of the apparatus. Fig. 2 shows the card table with the clamping mechanism for the cards, in front elevation, on an enlarged scale, and partly broken away. Fig. 3 is a plan view of Fig. 2; Fig. 4 shows the adhesive-container in plan view; Fig. 5 is a vertical section taken on line V—V of Fig. 4. Fig. 6 50 shows the sample-container in plan view; Fig. 7 is a vertical section taken on line VII—VII of Fig. 6; Fig. 8 is a side elevation of the inking mechanism and of the slide with the sample- 55 container, partly broken away; Fig. 9 is an end elevation of the apparatus as seen from the right in Fig. 1; Fig. 10 shows, on an enlarged scale, the jaw of the clamp, in longitudinal section, in 60 the closed position and (in broken lines) in the open position; Fig. 11 is a plan view corresponding to Fig. 10; Fig. 12 is a horizontal section taken through the slide on line XII—XII of Fig. 13, the sample-container, which is not visible, 65 being shown in broken lines; Fig. 13 is an end elevation of Fig. 12; Fig. 14 is a view similar to that of Fig. 12, and Fig. 15 a view similar to that of Fig. 13, only with the sample-container in a different position; Fig. 16 shows, in longitudinal 70 section, a detail of the slide with the sample- container lowered; Fig. 17 is a view corresponding to that of Fig. 16, only with the sample- container raised; Figs. 18, 19, 20 show diagrammatically the sample-container in three positions during its forward movement; Fig. 21 is a 75

perspective view of a printing block with short types inserted in position.

Like reference characters denote like parts in the several figures of the drawings.

Referring to the drawings, and in particular 5 to Fig. 1, the apparatus has a vertically reciprocatable head 1 provided at the sides with guides 2 for the card to mount, and a slide 3 on which there are provided an adhesive-container 4 and a sample-container 5. The slide is adapted to 10 travel on a horizontal track or bed 6 between stops 7 and 8 which are so disposed that in the one end position the adhesive-container 4, and in the other end position the sample-container 5 comes opposite the card secured to the under 15 side of the head or plunger 1.

In the container 4 there are disposed pads 10 of felt or other absorbent material (Fig. 4), and in the container 5 there are inserted open boxes 11 with stacks of samples 12 (Fig. 6). In one 20 working operation the plunger 1, together with the card inserted therein is lowered down on to the adhesive-container 4 with the result that an impression of the adhesive is applied to the card. In a second working operation the areas to which 25 adhesive has thus been applied are pressed on to the stacks of samples 12 in the sample-containers 5 with the result that the uppermost samples in the stacks are gummed to the card. At the same time the card guides 2 are pivoted 30 about joints 13 to detach the card from the plunger head 1. The mechanism for effecting the detaching of the card, and the arrangement of the boxes which receive the stacks of samples are not illustrated in the drawings, so as to show 35 more clearly the parts to which the invention relates.

The insertion of the cards in the plunger head 1, in the apparatus according to the present invention, is effected not by hand as hitherto, but 40 automatically. For this purpose there is provided in front of the plunger head 1 a card table which consists of a sloping plate 15 supported on a strut 16. The strut is capable of being fixed in position on a horizontal plate 17 which is slideable in guides 18, and which, in response to spring action, presses the table 15 together with the cards 19 leant against it, constantly up to rolls 20. These rolls 20 are provided, over a part of 45 their periphery, with a rubber covering 21 adapted to engage the uppermost card for the purpose of withdrawing the same from the stack. The rolls are rotated by gear wheels 22 actuated by a rack 23 terminating in a spring fork 24 in which a driver 25 attached to the slide 3 engages 50 with its spherical portion 26.

The card withdrawn from the stack by the action of the rolls 20 is gripped at an appointed time by clamps 30 which draw the card into the guides 2 in the plunger head.

The clamps 30 are disposed on arms 31 which are hinged to the slide 3 at 32, and are kept depressed by an angle piece 33 attached to the driver 25 to prevent the clamps from being pivoted upwards about the joints 32 when the card is being withdrawn. 34 denotes a stop on the slide against which the arms 31 may bear. The jaws 30a of the clamps are rigidly connected to the arms 31 (Figs. 10, 11), and the jaws 30b are hinged to the jaws 30a. The jaws 30b may on the one hand be pivotally moved by a cam 37 through the instrumentality of an arm 35 secured to this jaw and having a nose 36 at its end, and on the other hand are stressed by a leaf spring 39 which is supported against a leaf

spring 38 secured to the arm 31. The shafts of the cams 37 are connected to an arm 47. 40 is an arm which is formed integrally with the arm 31, and which is provided at the lower end with 5 a roller 41.

The controlling of the clamps 30 is effected by means of a guiding track 42 secured to the guideway or bed of the slide. The track 42 consists of horizontal portions 42b and 42c intersecting by a deflecting portion 42a, and a sloping branch portion 42d adjoining the portion 42b.

For controlling the jaw 30b of the clamps there serve stops 43 and 44 (Fig. 1) which are adjustable on the arms 45 and 46, respectively, secured 15 to the guideway 6 for the slide.

For the purpose of explaining the functioning of the rolls 20 and clamps 30 the position of the parts shown in Fig. 1 of the drawings will be taken as the starting point, at which point the 20 adhesive-container 4 is opposite the plunger head 1 and the rolls 20 are not in engagement with the cards. On movement of the slide carrying the adhesive and sample-containers, to the left under the card table the spherical portion 26 of the 25 driver 25 snaps into engagement with the fork 24 and moves the rack 23 with the result that the rolls 20 are rotated. The movement of the slide has in the meantime concurrently effected a lifting of the clamps 30, by virtue of the fact that 30 the rollers 41 pertaining to the arms 40 and travelling beneath the portion 42c of the guiding track (position shown in chain-dotted lines in Fig. 2) are caused to run up the ramp portion 42d and after deflecting the portion 42a to pass on to the portion 42b of the track 42. On the attainment of the end position the jaws of the clamps 30, which have stood open during the movement, are closed. The closing of the jaws is effected by the stop 43 which encounters the arm 39 and swings it into the position shown in broken lines in Fig. 2, with the result that the cams 37 are rotated and brought out of engagement with the nose 36 on the arm 35. The spring 38 is thus free to expand, and, by acting upon the leaf spring 39, presses the jaw 30b of the clamps into the position of closure. In the meantime the rolls 20 have rotated and pushed the card withdrawn from the stack propped against the plate 15, into the mouth of the clamps.

On the return of the slide 3 into the position shown in Fig. 1 the clamps draw the card 19 into the guides 2 at the sides of the plunger head. At the same time, through the intermediary of the driver 25, the rack 23 is carried along by the 50 slide 3 until the lug 48 on the rack (Fig. 3) strikes against a fixed stop 49. On the further movement of the slide 3 the driver 25 is consequently detached from the rack 23, the spherical portion 26 coming out of engagement with the fork 24. During this movement of the rack 23 the gear wheel 22 is disengaged from the axle of the rolls 20 by a free-wheel device not shown in the drawings, so that the rolls are not rotated.

The arms 49 of the clamps travel, during the return movement of the slide, on the portions 42b, 42a and 42c of the track 42. Shortly before attainment of the end position the arm 47 strikes against the fixed stop 44 (Fig. 1), with the result that the cams 37 are rotated in the direction which brings about opening of the clamps. Finally, the arms 49 come clear of the tracks 42 and are swung downwards under the influence of their own weight.

The card inserted in the plunger head 1 is pressed, when the plunger descends, on to the felt

pads 10 in the adhesive-container 4. In the known machines for the production of sample cards the area to be covered by the cards is coated with adhesive by the sucking action of the pads. The amount of adhesive applied to the 5 area of the cards to be covered in this manner is only constant, however, provided the liquid in the adhesive container be kept at a constant level. In practice this requirement can only be fulfilled with difficulty, and recourse is therefore had to the expedient of applying adhesive 10 from time to time to the sides of the pads.

In the apparatus according to the present invention this applying of adhesive is carried out automatically. To this end the adhesive pads 10 15 (Fig. 4) are surrounded by wires 51 which form a frame 52. This frame rests upon leaf springs 53 (Fig. 5) and is guided on pins 54. 55 are upwardly extending pins against which the plunger head 1 strikes in its descent. In this manner the 20 frame is pressed down and the wires 51 thereof are thereby caused to dip into the supply of adhesive 56 in the container and, on the up-stroke of the head 1, moisten the sides of the pads 10 with adhesive since the frame is raised again 25 under the action of the springs 53 and wipes against the sides of the pads. To enable the moistening action to be regulated the frames 52 are made vertically adjustable.

In the sample-container 5 there are provided 30 the boxes or compartments for the stacks of samples, with which are associated printing chases 58, and also further printing chases 59. The cards are numbered with the aid of the chases 58, while the chases 59 are used for printing the 35 required heading comprising for instance the name of the manufacturing company and a designation of the material from which the sample is taken. The printing blocks or forms may be composed of types or may consist of embossed 40 sheet metal attached to a wooden foundation.

According to Figs. 16, 17, and 21 the printing forms consist of chases with flanges 93 on opposite sides which engage in grooves 94 in the letters 91, these latter being preferably of the short 45 type. The letters are inserted into the longitudinal slot 90 formed between the flanges, and retained in position by means of spring quoins 92. The chases may be made, as shown in the drawings, of a strip of sheet metal 88 bent into 50 U-shape, the sides of which being spaced by blocks 89, or they may be made of synthetic resin, for instance Bakelite, or the like.

The forms are inked by an inking roll 60 pertaining to an inking apparatus 61. The inking apparatus is shown in the drawings as secured to the vertically reciprocatable head 1 of the device, it being however, understood that it may also be mounted to a stationary portion of the device. The roll 60 of the inking apparatus 61 is so supported on a rocking arm 62 that in the one position (shown in broken lines in Fig. 8) this roll is in contact with the distributing roll, while in the other position (shown in full lines) it travels over the surface of the forms. A spring 63 60 arrests the inking in either of the two end positions.

The arm 62 is hinged to a system of levers 64, 65 which is controlled by the slide 3. For this purpose there is mounted on the lever 64 a roller 66 which coacts with cam slots 67 and 68 in the 70 slide. When the slide is moved from left to right (Fig. 1) the roller 66 engages in the slot 67, with the result that the lever 64 is drawn downwards and the arm 62 swung downwards, so that the roller 66 travels across the face of the forms. 75

Shortly before the attainment of the end position, the roller 66 comes into engagement with the slot 68 and brings about the rocking back of the arm 62. When the slide is moved from right to left the roll 60 remains in the lifted position. To prevent the slot 67 from interfering with the return movement the portion 67a of the side thereof is adapted to hinge inwards to deflect the roller 66.

10 To ensure that the printing ink is uniformly applied to the forms in the inking operation the inking roll must travel over the face of the forms without any relative sliding movement. This result is achieved in accordance with the invention by fitting to the ends of the axle of the inking roll 60 milled-edged discs 69 of the same diameter as the inking roll, which run uninterruptedly on rails 70 throughout the inking operation and positively rotate the inking roll (Figs. 8 and 9). The rails, which are preferably provided with a rubber covering 70a, are disposed at both longitudinal sides of the sample-container 5 and secured to the slide 3. The rail surface on which the discs or wheels 69 run is slightly below the level of the surface of the forms, so as to cause the types to penetrate somewhat into the material of the inking roll, which is preferably made of gelatine, and thus to ensure thorough inking.

As may be seen from Figs. 6 and 7, the open boxes 11 are not directly inserted in the container 5 but are placed in an intermediate container 71 which may conveniently be made of cardboard or the like. The intermediate container 71 forms a frame for the boxes 11, the forms 58 and 59, and distancing elements 72 used to fill out the space between the boxes and the side walls of the intermediate container.

The use of an intermediate container affords the advantage that all preparatory work may be carried out independently of the machine, so that no time need be lost in going over to the production of a fresh set of sample cards.

The printing forms 58 and 59 are provided with pins 73 adapted to pass through holes in the bottom of the intermediate container and to rest upon resilient pins 74. In this manner the pressure is caused to be even on all forms, even if there should happen to be unevennesses in the surface of the forms. To avoid smudging of the print on the cards the forms are lowered after inking and remain in this position until the next inking operation. During the printing operation the forms emerge, since the sample-container is pressed down by the plunger head.

The lowering or submerging of the forms after inking and their raising prior to printing is effected by the following arrangement. The sample-container 5 rests upon four pins 80 which are resiliently mounted in sleeves 79, and which are capable of being moved up and down. For this purpose two fingers or cams 81 secured diametrically opposite each other on the slide 3 engage in helical grooves 82 of the sleeves 79. At the lower ends of the sleeves there are secured arms 83. The two pins 80 on one side of the container 5 are coupled together, through the intermediary of these arms, by a cranked rod 84; at the end of this rod there is fitted a roller 85 which is controlled by arcuate guides 86, 87 (Figs. 1, 8, 12-15, and 18 to 20) mounted on the stationary bed 6 of the apparatus. Owing to the interengaging pins and slots 81, 82, the pins 80 are raised or lowered, taking the sample-container with them, when the arms 83 are moved across from side to side. During this movement of the sample-con-

tainer the forms 58, 59 remain stationary therein, since the forms are supported independently of the sample-container. Consequently, when the sample-container is lifted the forms become submerged in the compartments of the container 5 and the surface of the types is brought below the level of the upper edge of the container (Fig. 17). When the sample-container is lowered the types emerge again (Fig. 16).

When the sample-container on the slide is moved beneath the plunger head 1 the types become inked by the inking roll 60 in the described manner. Prior to inking, the sample-container is in the raised position in which the types 91 are submerged. To allow of inking of the types the container is then lowered while being moved from the end position (Fig. 18) beneath the plunger head (position Fig. 20); in the course of this movement the rollers 85 travel over the arcuate guides 86 (Figs. 12, 13), are thereby shifted as to position (position in Fig. 19, as also in Figs. 14 and 15) and effect rocking of the arms 83 and consequently also rotation of the sleeves 79, this rotary movement being in turn converted, through the intermediary of the slots 82 and fingers 81, into a descending movement of the sleeves 79 together with the pins 80 (Fig. 16). The types consequently emerge from the container 5 and can come in contact with the inking roll 60. After the whole of the types has become inked the inking roll is swung up again in the manner already described, and the sample-container, in the course of its further movement, is lifted until it occupies a position beneath the plunger head (position of the end of the sample-container shown in broken lines in Fig. 8), by virtue of the fact that the rollers 85 travel over the arcuate guides 87 (Figs. 14, 15) and bring about a lifting of the pins 80 (Fig. 17) so that the sample-container comes into position with submerged types beneath the plunger head. The card is then printed and at the same time the samples are gummed on. The slide 3 is then moved back into the end position, so that the finished card may be removed and inserted into the nip of rolls 95, 96 kept in rotation behind the bed of the slide. These rolls are designed to deliver the card on to a ramp 97 (Figs. 1, 8 and 9) down which the same passes to a collecting box not shown in the drawings. The guides 86 are spring-stressed (Figs. 12, 13) so that they may yield to and clear the rollers 85 during the return movement of the slide into the end position (from position Fig. 18 to that of Fig. 20).

By combining the apparatus with a printing device capable of printing all the matter required to appear on the cards, considerable advantages are obtained over the hitherto usual method of printing companies' names and other matter on the cards in a separate working operation, since in this manner the length of time required to produce the cards is shortened and it becomes unnecessary to keep printed cards in stock.

After the printing of the cards and the gumming on of the samples the cards must be powerfully pressed, to cause the samples to adhere firmly. Hitherto it has been usual to use presses of the type of copying presses. The specific pressing force exerted by presses of this type is, however, relatively low, so that it has been necessary to leave the cards for a considerable length of time in the press.

The passing of the cards, after gumming, between the rolls 95, 96, as described, enables this

subsequent pressing to be carried out in a shorter time.

According to the provisions of the patent statutes, I have explained the principle and construction of my invention and have illustrated and described what I now consider to represent its best embodiment. However, I desire to have it understood that, within the scope of the appended claims, the invention may be practised otherwise than as specifically illustrated and described.

What I claim is:—

1. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head.

2. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms associated with said sample-container, an inking mechanism for inking said printing forms, and means mounted to said slide for controlling the said inking mechanism so as to ink said printing forms on the movement of said slide along said bed.

3. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, adhesive applying members provided in said adhesive-container, means for wetting said members and adapted to be controlled by said head, printing forms associated with said sample-container, an inking mechanism for inking said printing forms, and means mounted to said slide for controlling the said inking mechanism so as to ink said printing forms on the movement of said slide along said bed.

4. In an apparatus for mounting samples on backing, such as a sample card, folder, etc., a vertically reciprocatable head provided with guides for carrying a backing, a bed underneath said head, a stack of backings provided at one end of said bed, a slide positively guided on said bed, gripping elements actuated by said slide and adapted to withdraw the uppermost backing from said stack, clamping means associated with said slide and adapted to receive said uppermost backing from said gripping elements and to draw said backing into the guides of said head, an adhesive-container and a sample-container provided on said slide, printing forms associated with said sample-container, an inking mechanism for inking said printing forms, and means mounted to said slide for controlling the said inking mechanism so as to ink said printing forms on the movement of said slide along said bed.

5. In an apparatus as claimed in claim 4 gripping elements consisting of rolls frictionally engaging the uppermost backing of said stack of backings and adapted to be rotated by said slide so as to withdraw said uppermost backing.

6. In an apparatus for mounting samples on backing, such as a sample card, folder, etc., a vertically reciprocatable head provided with guides for carrying a backing, a bed underneath said head, a stack of backings provided at one end of said bed, a slide positively guided on said bed, gripping elements actuated by said slide on the movement of said slide in the direction towards the gripping elements and adapted to withdraw the uppermost backing from said stack, clamps hinged to said slide and adapted to receive said uppermost backing from said gripping elements and on the movement of said slide in the direction opposite to that first mentioned direction to draw said backing into the guides of said head, said clamps being swung down on the movement in the second mentioned direction after having passed the head, and raised on the movement in the first mentioned direction after having passed the head, an adhesive-container and a sample-container provided on said slide, printing forms associated with said sample-container, an inking mechanism for inking said printing forms, and means mounted to said slide for controlling the said inking mechanism so as to ink said printing forms on the movement of said slide along said bed.

7. In an apparatus for mounting samples on backing, such as a sample card, folder, etc., a vertically reciprocatable head provided with guides for carrying a backing, a bed underneath said head, a stack of backings provided at one end of said bed, a slide positively guided on said bed, gripping elements actuated by said slide on the movement of said slide in the direction towards the gripping elements and adapted to withdraw the uppermost backing from said stack, clamping means associated with said slide and adapted to receive said uppermost backing from said gripping elements and on the movement of said slide in the direction opposite to that first mentioned direction to draw said backing into the guides of said head, said clamping means consisting of a stationary jaw and a pivoted jaw, a spring tending to close said jaws, a cam causing said jaws to open against the action of said spring, stops provided on said bed and adapted to control said cam so as to close the jaws after the backing has been inserted therein by said gripping means and to open said jaws after the backing has been inserted in the guides of said head, an adhesive-

an inking roll mounted on a pivoted lever, and means mounted to said slide for controlling the said lever on the movement of said slide along said bed so as to cause said inking roll alternatively to engage said distributing roll and the face of said forms thus alternately distributing ink on said inking roll and inking said forms.

9. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms associated with said sample container, an inking mechanism for inking said printing forms comprising an ink distributing roll and an inking roll mounted on a pivoted lever, guides mounted to said slide, and a system of levers actuated by said guides on the movement of said slide along said bed so as to cause said inking roll alternately to engage said distributing roll and the face of said forms thus alternately distributing ink on said inking roll and inking said forms.

10. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms associated with said sample container, an inking roll for inking said printing forms, means mounted to said slide for controlling the said inking roll so as to ink said printing forms on the movement of said slide along said bed, rails fixed to said slide, and discs secured to said inking roll and adapted to run on said rails so as positively to rotate said inking roll during the inking operation.

11. In an apparatus as claimed in claim 10, discs secured to the axle of said inking roll and having the same diameter as said inking roll, and rails the surface of which lies slightly below the level of the face of said forms.

12. In an apparatus for mounting samples on backing, such as a sample card, folder, etc., a vertically reciprocatable head adapted to carry a backing, a bed underneath said head, a slide positively guided on said bed, an adhesive-container and a sample-container provided on said slide, adhesive applying pads provided in said adhesive-container, a vertically movable frame surrounding and adapted to wipe against the sides of said pads, a spring holding said frame in raised position, said frame being adapted to be moved downwards by the descending head so as to dip said frame in the body of adhesive provided in said adhesive container, and to raise upwards by the action of said spring so as to wipe against and moisten the sides of the pads with the adhesive carried by the frame.

13. In an apparatus for mounting samples on backing, such as a sample card, folder, etc., a vertically reciprocatable head adapted to carry a backing, means for inserting a backing in said head, a bed underneath said head, a slide positively guided on said bed, means provided on said

slide for controlling said inserting means on the movement of said slide along said bed so as to insert a backing in said head, an adhesive-container and a sample-container provided on said slide, adhesive applying pads provided in said adhesive-container, a vertically movable frame surrounding and adapted to wipe against the sides of said pads, a spring holding said frame in a raised position, said frame being adapted to be moved downwards by the descending head so as to dip said frame in the body of adhesive provided in said adhesive-container, and to raise upwards by the action of said spring so as to wipe against and moisten the sides of the pads with the adhesive carried by the frame, printing forms associated with said sample-container, an inking mechanism for inking said printing forms, and means mounted to said slide for controlling the said inking mechanism so as to ink said printing forms on the movement of said slide along said bed.

14. In an apparatus for mounting samples on backing, such as a sample card, folder, etc., a vertically reciprocatable head adapted to carry a backing, a bed underneath said head, a slide positively guided on said bed, an adhesive-container and a sample-container provided on said slide, an intermediate container containing stacks of samples and adapted to be inserted in said sample-container, printing forms associated with said intermediate container, an inking mechanism for inking said printing forms, and means mounted to said slide for controlling the said inking mechanism so as to ink said printing forms on the movement of said slide along said bed.

15. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, an intermediate container containing stacks of samples and adapted to be inserted in said sample-container, printing forms associated with said intermediate container, an inking mechanism for inking said printing forms, and means mounted to said slide for controlling the said inking mechanism so as to ink said printing forms on the movement of said slide along said bed.

16. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms associated with said sample-container and resilient pins adapted to support said printing forms, an inking mechanism for inking said printing forms, and means mounted to said slide for controlling the said inking mechanism so as to ink said printing forms on the movement of said slide along said bed.

17. In an apparatus as claimed in claim 2 printing forms consisting of printing letters with longitudinal grooves, and of letter carrying mem-

bers with oppositely disposed flanges adapted to engage said grooves.

18. In an apparatus as claimed in claim 2 printing forms consisting of printing letters with longitudinal grooves and of U-shaped metal strips with oppositely bent in ledges adapted to engage the grooves of said printing letters.

19. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms housed in said sample-container, an inking mechanism for inking said printing forms, means mounted to said slide for controlling the said inking mechanism so as to ink said printing forms on the movement of said slide along said bed, and means adapted to raise and lower said sample-containers independently 25 of said printing forms so as to enable the forms to be submerged beneath and protruded above the surface of the sample-container.

20. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to insert a backing in said head, an adhesive-container and a sample-container provided on said slide, printing forms associated with said sample-container and resting on a resilient support, 35 sleeves journaled in said slide axially slidable resilient pins projecting from said sleeves and supporting said sample-container, a lever system adapted to rotate said sleeves, a helical groove provided on said sleeves, cams fixed to said 40 slide and engaging said grooves so as to convert the rotation of the sleeves into an axial movement, arcuate guides provided on said bed and adapted to control said lever system on the movement of said slide so as to displace said lever system causing rotation of the sleeve and axial movement of said pins imparting the latter movement to the sample container.

21. In an apparatus for mounting samples on backing, such as a sample card, folder, etc., a vertically reciprocatable head adapted to carry a backing, means for inserting a backing in said head, a bed underneath said head, a slide positively guided on said bed, means provided on said slide for controlling said inserting means on the movement of said slide along said bed so as to

insert a backing in said head, an adhesive-container and a sample-container provided on said slide, printing forms associated with said sample-container, an inking mechanism for inking said printing forms, and means mounted to said slide for controlling the said inking mechanism so as to ink said printing forms on the movement of said slide along said bed, and pressing rollers mounted to said bed and adapted to receive and press the backing with the sample mounted 10 thereon.

22. An apparatus for mounting samples on cards and the like, comprising a head for carrying a card, a bed underneath said head, a slide positively guided on said bed, an adhesive-container and a sample-container mounted on said slide, adhesive-applying members provided in the adhesive-container, means for inserting a card in said head, means provided on said slide for controlling the card-inserting means and the inking mechanism on the movement of said slide so as to insert a card in said head and means for alternately lowering said head over said adhesive container so as to apply adhesive to the said card, and over said sample-container so as to cause 25 the samples to adhere to said card.

23. An apparatus for mounting samples on cards and the like, comprising a head for carrying a card, a bed underneath said head, a slide positively guided on said bed, an adhesive-container and a sample-container mounted on said slide, adhesive-applying members provided in the adhesive-container, forms associated with the sample-container, an inking mechanism for inking said forms, means for inserting a card in said head, means provided on said slide for controlling the card-inserting means and the inking mechanism on the movement of said slide so as to insert a card in said head and to ink said forms, and means for alternately lowering said head over said adhesive-container so as to apply adhesive to the said card, and over said sample-container so as to cause the samples to adhere to said card and to print said card with the aid of said forms.

24. An apparatus for mounting samples on cards, and the like, comprising a head for carrying a card, a bed underneath said head, a slide positively guided on said bed, an adhesive-container and a sample-container mounted on said slide, adhesive applying members provided in the adhesive-container, means for wetting said adhesive applying members and adapted to be controlled by said head, and means for alternately lowering said head over said adhesive-container so as to wet said adhesive-applying members and to apply adhesive to said card, and over said sample-container so as to cause the samples to adhere to said card.

ALFRED OSER. 60
